TANK

Gwynne Raymond and Lee E. Young, Oklahoma City, Okla., assignors to Black, Sivalls & Bryson, Inc., Oklahoma City, Okla., a corporation of Maine

Application July 20, 1936, Serial No. 91,500

10 Claims. (Cl. 217—4)

This invention relates to tanks, and particularly to those for containing corrosive fluids under differential internal and external pressures.

Tanks of this character may be constructed of wood or similar materials not affected by the corroding or disintegrating influence of the contained liquids, but it is essential that metallic parts be incorporated in the wood construction to enable the tank to withstand the differential pressures. The metal parts contained within the tank must, therefore, be sealed against exposure to the corrosive fluids. For these reasons construction and assembly of this type of tank have been made difficult.

It is, therefore, the principal object of the present invention to provide a composite tank construction wherein the metal parts are effectively sealed from the corroding or disintegrating effects of the contained fluids and which may be readily assembled in a facile manner.

In accomplishing this and other objects of the invention, we have provided improved details of structure, the preferred form of which is illustrated in the accompanying drawings, where-

25 in:

Fig. 1 is a perspective view of a tank embodying the features of the present invention, a part of the tank wall being broken away to show the supporting tying-in structure between the heads of the tank.

Fig. 2 is a horizontal section through the tank on the line 2—2, Fig. 1.

Fig. 3 is an enlarged fragmentary section through the upper and lower portions of the tank adjacent the side wall thereof, particularly illustrating tying of the shoring to the tank heads.

Fig. 4 is a section on the line 4—4 of Fig. 3.

Fig. 5 is a disassembled perspective view of the stringers, shoring and footing plates.

40 Referring more in detail to the drawings:

1 designates a tank constructed in accordance with the present invention, and which includes a circular side wall 2 formed by a plurality of vertical staves 3 having transverse notches 4 and 5, adjacent their ends, forming peripheral grooves 6 and 7, and in which the peripheral edges 8 and 9 of upper and lower heads 10 and 11 are seated.

The lower head 11 constitutes the floor or bottom of the tank, and is made up of a plurality of boards 12 having their edges 13 and 14 arranged in sealing contact and provided with dowels 15 for retaining the upper and lower surfaces of the boards in the same relative plane. The upper head 10 constitutes the roof or upper deck of the tank and is made up of boards 16, similar to

the lower deck, except that cooperage strips 17 are inserted between the adjacent edges of the centermost boards, the dowels in these joints being omitted.

The staves composing the side wall 2 are retained in sealing relation with each other and secured against the heads by encircling tie rods or hoops 18 as shown in Fig. 1. The upper ends of the staves are encircled by a flat band 19 that is driven over the ends thereof, as shown in Fig. 1.

The tank construction thus far described conforms to that of a conventional tank constructed of staves, however, in tanks of large diameter, such as are used in storing petroleum, it is necessary to provide means for supportingly spacing 15 and tying the centers of the heads and to retain the heads in their proper relation when differential pressures occur between the interior or exterior of the tank. For example, when the tanks contain petroleum oils under pressure, the pressure acts to cause bulging of the heads in an outward direction, and when the tank is being emptied of oil should the vent fail to act, or when the oil contracts because of low temperature, the pressure drops therein below the external 20 pressure, causing the heads to buckle inwardly unless means is provided for supporting the heads 25 in their proper relation.

The interior of the tank is, therefore, provided with shoring which, in the illustrated instance, 30 comprises pairs of posts 20, 21, 22 and 23, having their lower ends supported on footing plates 24, 25, 26 and 27 respectively, that engage against the upper face of the lower head and extend transversely across the width of the boards 12, 35 as best shown in Fig. 1, the posts being arranged on opposite diametrical sides of the tank, and in planes parallel with a plane passing through the center of the tank. The upper ends of the posts support stringers 28 and 29 which are shown as 40 comprising flat planks having their ends resting upon the pairs of posts and their upper surfaces engagingly supporting the head 10.

The shoring structure thus described is tied to the heads of the tank by means of stud bolts 30 45 and 31 for the ends of each of the respective posts. In accordance with the present invention the stud bolts are completely insulated from the fluids contained in the tank by shielding them in the interior of the wooden parts which they 50 connect, and are so mounted therein as to facilitate assembly of the tank, as hereinafter described.

The lower stud bolts 31 have their upper ends extending through axial bores 32 provided in the 55

bottom ends of the posts to threadedly connect with anchor members 33 that are mounted in transverse openings 34 extending transversely through the posts at points spaced from the lower 5 ends thereof. The anchor members are preferably formed of metal and of substantially cylindrical shape to closely fit within the openings 34, but are of shorter length than the thickness of the posts so that the ends 35 and 36 thereof are 10 spaced from the adjacent side faces 37 and 38 and provide recesses 39 and 40 into which insulating plugs 41 and 42 are driven to seal the anchoring members from contact with the contents of the tank, the plugs 41 and 42 being preferably wedged within the recesses and further sealed by a suitable cement impervious to corrosive action of the fluid.

The anchoring members 33 are provided with threaded sockets 43, aligning with the bores 32, 20 to engage the threaded ends 44 of the stud bolts 30. The lower ends 45 of the studs extend through aligning openings 46 and 47 in the respective footing members and in the underlying floor boards 12 respectively, the openings 46 being 25 of sufficient diameter to accommodate nuts 48 that are threaded on the stud bolts, but the openings 47 are of suitable size to snugly fit the stud bolts, thereby providing shoulders 49 for seating washers 50 that are clampingly retained against 30 the floor boards by the nuts 46.

The stud bolts 30 are similarly mounted in axial bores 51 in the upper ends of the posts and have threaded ends 52 threadedly engaging in the sockets of similar anchor members 53 located 35 in transverse openings 54 of the posts. The upper ends of the stud bolts project through aligning openings 55 and 56 in the stringers 28 and 29 and in the overlying boards of the roof deck respectively. The bolts are of sufficient length to project a material distance from the boards, and are 40 provided with threads to mount nuts 57 which retain washers 58 thereon in clamping engagement with the roof board and to effect drawing of the boards against the stringers 28 and 29, and the stringers tightly against the upper ends 45 of the posts. To further enhance the seal at the ends of the posts a suitable tank cement is applied thereon prior to drawing up of the stud bolts.

The structure thus far described provides supports to prevent inward buckling of the tank 50 heads under external pressures, and in order to prevent outward buckling of the heads when the internal pressures exceed the external pressures, the lower stud bolts 31 project through openings 59 in clamping plates 60 that cooperate with footing plates to clamp the lower head therebetween 55 when nuts 61 are threaded on the stud bolts, as shown in Fig. 3.

The nuts 61 include washer-like flange portions 60 62 having prongs or spurs 63 for projection into the body of the clamping plates to prevent rotation of the nuts when the stud bolts are drawn up in the assembly of the tank, as later described.

Cooperating with the stringers 28 and 29 are 65 clamping stringers 64 and 65 that extend transversely across the outer surfaces of the roof boards, and which are provided with counter-bored openings 66 extending therethrough to allow projection of the upper ends of the stud bolts 70 and to accommodate the nuts 51.

In order to anchor the clamping stringers, the free ends of the stud bolts are provided with washers 67 and clamping nuts 68, as best shown in Fig. 3. The stringers are of sufficient length 75 to extend substantially across the tank, and the

outer or unsupported ends thereof are clamped together and to the roof boards by stud bolts 69 which extend through aligning openings 70, 71 and 72 in the ends of the stringers and roof board, respectively, the ends of the stud bolts being threaded and provided with washers and nuts 73 and 74. The nuts 75 on the interior of the tank preferably are of non-corrosive material and are of cap form to protect the stud bolt from the corroding influence of the liquid in the 10 tank.

With the construction thus described it is clearly obvious that the stud bolts are completely shielded from the corrosive action of the fluid since they are completely closed within the parts 15 which they connect. They also permit of ready assembly of the tank, as now to be described.

In assembling the tank, the floor boards having the openings 47 are turned on edge and the nuts 48 are run onto the studs 31 a sufficient 20 distance to accommodate the boards and clamping plates, and to allow sufficient projection for accommodating the nuts 61.

The stud bolts are then projected through the openings in the planks and openings 59 in the 25 bottom clamping plates. The nuts 61 are then applied to the projecting ends of the stud bolts, after which the nuts 48 are drawn tightly against the head to cause the prongs on the nuts 61 to be drawn into the clamping plates, thereby prevent- 30 ing rotation of the nuts 61.

The footing plates are then applied so that the openings 46 therein pass over the nuts 48 to lie crosswise of the flooring boards. The openings 46 are then filled over the nuts with tank cement. The anchoring members 33 are then inserted in the 35 openings of the posts and the posts are slid longitudinally onto the stud bolts. The lower ends of the posts are then smeared with tank cement and the threaded ends of the stud bolts 40 are caused to engage in the threaded sockets of the anchoring members. The posts are then rotated to tighten the ends thereof rigidly against the footing plates. The recesses 39 and 40 are then closed by the plugs 41 and 42 and tank cement. The posts are then up-ended, laying the 45 bottom board flat. The anchor members 53 are then inserted in the transverse openings 54 at the upper ends of the posts, and the stud bolts 30 are inserted in the axial bores 51 to threadedly 50 engage in the sockets of the anchoring members. The top of the post is then smeared with tank cement and the inner stringers 28 and 29 are applied to the upper ends of the posts so that the stud bolts project through the openings 55 there- 55 in.

The roof boards are then put in place on the stringers. The washers 58 are then inserted over the projecting ends of the stud bolts to bear against the roof boards, after which the nuts 57 60 are applied and screwed tightly against the washers to draw the ends of the posts into sealing contact with the stringers 28 and 29. The clamping stringers 64 and 65 are then mounted on the tank, after which the washers 67 and nuts 68 are 65 applied to draw them into cooperative clamping contact with the roof boards. The stud bolts 69 may then be applied to complete the assembly of the stringers. The recesses in the ends of the anchoring members are then closed by the plugs 70 and tank cement, in the same manner as previously described in connection with the lower anchor members 33. After assembly of the heads 75 the staves composing the wall 2 may be assembled around the peripheral edges thereof and 75

secured in position by the hoops, as in conventional practice.

From the foregoing, it is obvious that the shoring which includes the pairs of posts is readily assembled, and is effective in meeting both internal and external pressures. It is also obvious that the metal parts composing the ties are hermetically sealed from the contents of the tank.

10 What we claim and desire to secure by Letters Patent is:

1. A tank for containing corrosive fluid under pressures varying above and below pressures exteriorly of the tank, including a side wall and upper and lower heads formed of material resistive to the corrosive action of the fluid, a footing member supported on the lower head, a post having its lower end mounted on said footing member, a stringer supported on the upper end of the post and supportingly engaging the upper head, said footing member, post and stringer being formed of material resistive to the corrosive action of the fluid, clamping members located exteriorly of the heads and respectively 25 cooperating with the footing member and stringer for clampingly engaging the heads, individual metallic tying means, means enclosingly anchoring the tying means in the respective ends of the post, clamping means respectively enclosed by the 30 upper clamping member and by the footing member and engaging the tying means for retaining the footing member and stringer in sealing contact with the ends of the post, and means on the tying means for drawing the clamping members 35 into clamping engagement with said heads.

2. A support for the upper and lower heads of a tank including a post having axial bores extending inwardly from the ends of the post and terminating in intersecting transverse bores, said 40 post and heads being formed of material resistive to corrosive action of fluid contained in the tank, anchoring members in the transverse bores, stud bolts in the axial bores and having ends connected with the anchoring members, means for closing the transverse bores to prevent contact 45 of the anchoring members with fluid contained in the tank, and means connecting the stud bolts with heads of the tank.

3. A support for the upper and lower heads of a tank including a post having axial bores extending inwardly from the ends of the post and terminating in intersecting transverse bores, anchoring members in the transverse bores, stud bolts in the axial bores and having ends connected 50 with the anchoring members, means for closing the transverse bores to prevent contact of the anchoring members with fluid contained in the tank, a footing member inserted between the lower end of the post and the lower head and 55 having an opening to pass the stud bolt at the lower end of the post, a stringer carried by the upper end of the post and having an opening for passing the stud bolt at the upper end of the post, and means for anchoring the stud bolts to the 60 upper and lower heads of the tank, said heads, post, footing member and stringer being formed of material resistive to corrosive action of fluid contained in the tank to protect the anchoring members and stud bolts from corrosion by said 65 fluid.

4. A support for the upper and lower heads of a tank including a post having axial bores extending inwardly from the ends of the post and terminating in intersecting bores extending trans- 70 versely through the post, anchoring members in

the transverse bores, means for closing the ends of the transverse bores, stud bolts in the axial bores and having connection with the anchoring members, a footing member inserted between the lower end of the post and the lower head and 5 having an opening to pass the stud bolt at the lower end of the post, a nut on said lower stud bolt enclosed in said opening for engaging against the lower head, means on the stud bolt for engaging under the head to draw the post into sealing contact with the footing member and the footing member against said head, a stringer supported on the upper end of the post and having an opening to pass the stud bolt at that end of the post, and a nut on the upper stud bolt 10 engaging the outer face of the upper head to draw the head against the stringer and the stringer against the upper end of the post, said heads, post, footing member and stringer being formed of material resistive to corrosive action of fluid 15 contained in the tank for shielding the anchoring members, stud bolts and nuts from said corrosive action of the fluid.

5. A support for the upper and lower heads of a tank including a post having axial bores extending inwardly from the ends of the post and intersecting transverse bores in the post, anchoring members in the transverse bores, stud bolts in the axial bores and having ends connected with the anchoring members and their opposite ends extending through openings in said heads, means for closing the transverse bores to protect the anchoring members from the corrosive effects of fluid contained in the tank, a footing member inserted between the lower end of the post and the lower head and having an opening to pass the stud bolt at that end of the post, a nut on the stud bolt enclosed in said opening for engaging against the lower head, a clamping member engaging against the under face of the head and 25 having an opening for passing the stud bolt, a nut on the stud bolt for engaging the clamping member and cooperating with the first named nut to draw the clamping member to the lower head and the lower end of the post against the footing 30 member, a stringer carried by the upper end of the post and having an opening to pass the stud bolt at the upper end of the post, a nut on said upper stud bolt for drawing the head against the stringer and the stringer against the upper end of the post, a clamping stringer engaging the opposite side of the upper head and having an opening for passing the upper stud bolt, and a nut on the upper stud bolt for drawing the clamping stringer against the upper head, said heads, 35 post, footing member and first-named stringer being formed of material resistive to corrosive action of fluid contained in the tank for shielding the anchoring members, stud bolts and nuts from 40 said corrosive action of the fluid.

6. A support for the upper and lower heads of a tank including a post having bores extending inwardly from the ends of the post and intersecting transverse bores in the post, anchoring members in the transverse bores, stud bolts in the inwardly extending bores and having ends connected with the anchoring members and their opposite ends extending through openings in said heads, means for closing the transverse bores to 45 protect the anchoring members from the corrosive effects of fluid contained in the tank, a footing member inserted between the lower end of the post and the lower head and having an opening to pass a stud bolt, a nut on the stud bolt enclosed in said opening for engaging against the lower 50 head, a clamping member engaging against the under face of the head and having an opening for passing the stud bolt, a nut on the stud bolt for engaging the clamping member and cooperating with the first named nut to draw the clamping member to the lower head and the lower end of the post against the footing 55 member, a stringer carried by the upper end of the post and having an opening to pass the stud bolt at the upper end of the post, a nut on said upper stud bolt for drawing the head against the stringer and the stringer against the upper end of the post, a clamping stringer engaging the opposite side of the upper head and having an opening for passing the upper stud bolt, and a nut on the upper stud bolt for drawing the clamping stringer against the upper head, said heads, post, 60 footing member and first-named stringer being formed of material resistive to corrosive action of fluid contained in the tank for shielding the anchoring members, stud bolts and nuts from said corrosive action of the fluid.

head, a cement filling said opening over the nut, a clamping member engaging against the under face of the head and having an opening for passing the stud bolt, a nut on the stud bolt for engaging the clamping member and cooperating with the first named nut to draw the clamping member to the lower head and the lower end of the post against the footing member, a stringer carried by the upper end of the post and having an opening to pass the stud bolt at the upper end of the post, a nut on said upper stud bolt for drawing the head against the stringer and the stringer against the upper end of the post, a clamping stringer engaging the opposite side of the upper head and having an opening for passing the upper stud bolt, and a nut on the upper stud bolt for drawing the clamping stringer against the upper head, said heads, post, footing member and first-named stringer being formed of material resistive to the corrosive action of fluid contained in the tank for shielding the anchoring members, stud bolts and nuts from said corrosive action of the fluid.

7. A support for the upper and lower heads of a tank including spaced posts having bores extending inwardly from the ends of the posts and terminating in intersecting transverse bores, anchoring members in the transverse bores, stud bolts in the inwardly extending bores and having ends connected with the anchoring members, means for closing the transverse bores to prevent contact of the anchoring members with fluid contained in the tank, footing members inserted between the lower ends of the posts and the lower head and having openings to pass the stud bolts at the lower ends of the posts, a stringer carried by the upper ends of the posts and having openings for passing the stud bolts at the upper ends of the posts, and means for anchoring the stud bolts to the upper and lower heads of the tank, said posts, footing members and stringer being formed of material resistive to the corrosive action of the fluid to protect the anchoring members and stud bolts from contact by the fluid.

8. A tank for containing corrosive fluid under pressures varying above and below pressures exteriorly of the tank, including a side wall and upper and lower heads formed of material resistive to the corrosive action of the fluid, footing members having faces contacting the inner and outer faces of the lower head, posts having ends shaped to provide non-leakable contact with the inner footing members, stud bolts enclosingly an-

chored within the ends of said posts and having shanks extending through the footing members and said lower head, nuts threaded on the shanks for engaging the lower footing members, cooperative nuts covered by the inner footing members to engage the surfaces of the lower heads and cooperating with the first named nuts to anchor the post to the lower head whereby the post is retained in non-leakable contact with the footing members and the footing members against said lower head to complete a non-leakable seal about the stud bolts and nuts, and means for anchoring the upper ends of the posts to the upper head.

9. A tank for containing corrosive fluid under pressures varying above and below pressures exteriorly of the tank, including a side wall and upper and lower heads formed of material resistive to the corrosive action of the fluid contained in the tank, footing members extending across and having non-leakable contact with the inner and outer faces of the lower head, posts mounted on the inner footing members and having ends shaped to provide non-leakable contact with the inner footing members, individual tying means sealingly anchored within the ends of the posts and extending through aligning openings in the footing members and said lower head, means on the tying means for engaging said outer footing member, cooperative means completely enclosed in the openings of the inner footing members engaging the inner surface of the lower head and cooperating with the first named engaging means to anchor the posts and to maintain said non-leakable contacts, and means for anchoring the upper ends of the posts to the upper head.

10. In a tank formed of material resistive to corrosive action of fluid contained in the tank under pressures differential from pressures exteriorly of the tank, a support formed of similar material including a member having axial bores extending inwardly from the ends of said member and terminating in intersecting transverse bores, metallic anchor members in the transverse bores, stud bolts in the axial bores and having ends connected with the anchoring members, means closing the transverse bores to prevent contact of the anchoring members with the fluid contained in the tank, and means insulatingly connecting the stud bolts with the tank.
